CLAIM

The ornamental design for a portion of a syringe, as shown and described.

DESCRIPTION

FIG. 1 is a perspective view of a portion of a syringe showing our new design;

FIG. 2 is a side view of the portion of a syringe shown in FIG. 1; and

FIG. 3 is a bottom view of the portion of a syringe shown in FIG. 1; and,

FIG. 4 is a perspective view of an alternative embodiment of the portion of a syringe shown in FIG. 1 wherein the barrel portion of the syringe is transparent.
